US0D1060947S

(12) **United States Design Patent** (10) Patent No.: **US D1,060,947 S**
(45) Date of Patent: ** Feb. 11, 2025

(54) **CAP**

(71) Applicant: **RELIVE CO., LTD.**, Sendai (JP)
(72) Inventor: **Takashi Sasaki**, Sendai (JP)
(73) Assignee: **Relive Co., Ltd.**, Miyagi (JP)
(**) Term: **15 Years**
(21) Appl. No.: **35/517,493**

(22) Filed: **Apr. 11, 2023**(80) **Hague Agreement Data**

Int. Filing Date: **Apr. 11, 2023**
Int. Reg. No.: **DM/229343**
Int. Reg. Date: **Apr. 11, 2023**
Int. Reg. Pub. Date: **Jun. 9, 2023**

(30) **Foreign Application Priority Data**

Oct. 11, 2022 (JP) 2022-21953
Oct. 11, 2022 (JP) 2022-21954
Oct. 11, 2022 (JP) 2022-21955
(51) **LOC (15) Cl.** 02-03
(52) **U.S. Cl.**

(57) **CLAIM**

The ornamental design for cap as shown and described.

DESCRIPTION

1.1: Front

1.2: Back

1.3: Top

1.4: Bottom

1.5: Right

1.6: Left

1.7: Perspective

1.8: Reference bottom-side perspective view

The broken lines in reproduction 1.8 depict features of the cap that form no part of the claimed design.

1 Claim, 8 Drawing Sheets
